UNITED STATES PATENT OFFICE.

CLARE H. DRAPER, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

FILLING-END CONTROLLER FOR LOOMS.

Application filed October 26, 1921. Serial No. 510,489.

To all whom it may concern:

Be it known that I, CLARE H. DRAPER, a citizen of the United States, residing at Hopedale, in the county of Worcester and 5 State of Massachusetts, have invented certain new and useful Improvements in Filling-End Controllers for Looms; and I do hereby declare the following to be a full, clear, and exact description of the invention 10 such as will enable others skilled in the art to which it appertains to make and use the same.

The present invention relates to an improvement in filling end controllers for 15 looms.

The object of the invention is to produce a controller for the end of the filling extending from the filling end holder to the selvage after replenishment so as to hold it 20 out of the path of the lay. To the above end the present invention consists in the filling end controller hereinafter described and particularly defined in the claims.

In the accompanying drawings illustrating the preferred form of the invention, Fig. 25 1 is an end elevation of the hopper stand, showing the filling end controller in position with relation to the lay and shuttle box; Fig. 2 is a plan of the lay, showing the 30 position of the filling end controller with respect to the lay; Fig. 3 is an enlarged plan, showing the position of the parts at the time of the beat-up of the lay; and Fig. 4 shows the position of the parts on the back 35 center.

The illustrated embodiment of the invention is described as follows: The filling end controller consists of a wire 10 supported from the hopper plate 11, the rear end of 40 the wire being secured to a bracket 12 by a bolt 13, which bracket is secured by means of the bolt 14 to the block 17 which carries the sliding bobbin support, not shown. The hopper plate is supported on the bracket

45 15 provided with a foot 16, which is secured to the breast beam in the usual manner. The lay 20 is provided with shuttle boxes 21. The front box plate 22 is provided with a hook 23, which is adapted to engage 50 the thread extending from the shuttle to the filling end holder to move it forward, as shown in Fig. 3, beyond the forward end of the filling end controller 10, then as the lay moves rearwardly, the thread rides up

on the filling end controller to the position 55 indicated at 24 in Fig. 1, where it remains out of the path of motion of the shuttle box until it is cut off. The back box plate 25 is provided with a forwardly extending portion 26, constituting a shuttle guard, which 60 is notched at 27 to receive the forward end of the filling end controller when the lay is forward, as shown in Figs. 1 and 3. The filling end holder 30 is shown in Fig. 2, and indicates the position of the filling extending 65 from the holder to the shuttle on the first pick of the shuttle away from the replenishing side of the loom after replenishment.

On the first pick of the shuttle after replenishment, the filling 40 extends from the holder 30 through the shed, as shown in Fig. 2, and to the shuttle boxed in the shuttle box on the opposite side of the loom from the replenishing mechanism. On this 70 first pick of the shuttle, the filling is pulled out of the shuttle by the movement of the shuttle away from the replenishing mechanism, and extends on the diagonal line as shown. On the next forward beat of the 75 lay, the hook 23 on the front box plate engages this filling end 40 and pushes it forwardly into the position shown in Fig. 3, thereby causing the filling to be moved forwardly beyond the front end of the filling 80 end controller, as shown in Fig. 3. Now the filling end controller, extending as it does from its support on the hopper plate, is inclined downwardly and to the left as 85 shown, and after the filling has been carried beyond its front end and the lay begins to retreat, the filling catches over the end of the filling end controller and rides up on it and occupies the position shown in Fig. 4 90 above the shuttle box, and is thereby held out of the field of movement of the lay which is thus prevented from striking it on each forward beat thereof.

In the filling end controller of a former proposed construction, a hook is provided 100 supported from the breast beam of the loom and extended rearwardly therefrom over which the filling extending from the holder to the shuttle is hooked by a projection extended upwardly from the bracket mounted on the lay. At every forward beat of the lay this projection impinges against the filling end and is, therefore, liable to break it. 105

So also in another former construction in which a hook is mounted on the breast beam and extends rearwardly and then downwardly and forwardly, which is intended to 5 catch the filling end when the latter is moved forwardly by a projection on the front box plate of the lay. This operates in the respect named in the same manner as the first 10 mentioned construction because on each forward beat of the lay a projection comes in contact with the filling end and presses against it, whereas in the present construction, after the filling is once caught by the 15 filling end controller, the filling is lifted up out of the field of movement of the lay and is no longer subjected to the blows of the lay upon it. This obviates the danger of breaking the thread, due to the blows of the lay upon it, with the consequent liability of the 20 broken filling end extending from the selvage being whipped into the shed by the shuttle and causing an imperfection in the goods.

The loom may be provided with the usual 25 temple and thread cutter.

Having thus described the invention, what is claimed is:

1. A filling replenishing loom having, in 30 combination, a lay, weft replenishing mechanism, a filling end controller consisting of a slender rod supported at its rear end and extending forwardly and downwardly to a point less than the distance to which the filling is moved by the lay acting to lift the 35 filling on the next backward movement of the lay to a position above the field of movement of the shuttle box.

2. A weft replenishing loom having, in 40 combination, weft replenishing mechanism, a hook on the shuttle box, a filling end controller consisting of a stationary slender rod supported at its rear end and extended forwardly and downwardly into a position to catch an incoming filling end carried forward by the hook on the shuttle box.

3. A weft replenishing loom having, in 45 combination, a lay, weft replenishing mechanism, a filling end controller consisting of

a slender body supported at its rear end over the field of movement of the lay and 50 extending from its rear end forwardly in a downward and inward direction.

4. A filling replenishing loom having, in combination, a lay provided with a shuttle box, weft replenishing mechanism, a filling 55 end controller supported above the field of movement of the shuttle box, the back plate of the shuttle box being provided with a notch to receive the forward end of the filling end controller when the lay is on its 60 front center.

5. A filling replenishing loom having, in combination, a lay provided with a shuttle box, a filling end controller supported above the field of movement of the shuttle box, a 65 hook on the front box plate for engaging an incoming filling end, the back box plate being provided with a recess to receive the forward filling catching end of the filling end controller upon the forward beat of the lay. 70

6. A filling replenishing loom having, in combination, a lay provided with a shuttle box, weft replenishing mechanism, a filling 75 end controller supported above the field of movement of the shuttle box having its free end extended forwardly toward the breast beam, the back box plate being provided with a forwardly extended shuttle guard provided with a notch adapted upon the forward movement of the lay to receive the 80 front end of the filling end controller and the front box plate being provided with a hook adapted to carry the filling extending from the holder to the shuttle to move the filling forward beyond the front end of the 85 filling end controller.

7. A weft replenishing loom having, in combination, a lay, weft replenishing mechanism, a filling end controller supported at its rear end over the field of movement of 90 the lay and extending forwardly in a downward and inward direction, and provided with a small end to catch an incoming filling end.

CLARE H. DRAPER.
